METHOD OF MAKING HOLLOW PANELS

Oliver Clarence Davis, Louisville, Ky., assignor to
 The Mengel Company, Louisville, Ky., a corporation of New Jersey

Application June 12, 1942, Serial No. 446,817

7 Claims. (Cl. 144—309)

This invention relates to methods and apparatus for making structural units such as doors, walls, partitions, or the like, and, inasmuch as the invention may be utilized to great advantage in the making of doors, it will be illustrated and described specifically with reference to such structural units.

In recent years, the demand for a door that is light in weight, thermal insulating, fire-resistant, inexpensive to manufacture, structurally stable upon exposure to air of varying humidity, and workable and strong at its edge portions for receiving conventional hardware such as latches, door knobs, hinges, etc., has greatly increased.

Many structural arrangements have been advocated, but the method of making the same has become a very important consideration.

One very satisfactory structural arrangement for a door contemplates the use of a grid or filler of relatively soft material surrounded by a framework of relatively firm material constituting the rails or edge portions of the door, with facing members of wood veneer or plywood panels.

Such a door is shown in United States Letters Patent No. 2,173,808, issued September 19, 1939, to G. D. Kellogg.

In producing doors of this type, it is desirable to employ a lightweight thermal-insulating material for making the grid or filler of the core, such as fibre board of the kind frequently used for thermal insulation and weighing, for instance, 8 to 14 pounds to the cubic foot, and to employ a hot-setting glue for securing, in a short period of time, the facing members to the grid and framework assembly.

To obtain a satisfactory bond between the facing members, grid and framework, the aforesaid parts are preferably assembled in a hot-plate press, and subjected to relatively high pressures and temperatures for a time sufficient to set the glue.

However, the pressure required to assemble such structural units often injures the soft grid or filler, and produces a door having objectionable waves or similar imperfections on the outer surface of the facing members thereof.

Therefore, the primary object of the present invention is to provide a method of making such doors that will not only eliminate entirely the aforesaid objections, but greatly increase production efficiency.

Briefly, the method disclosed in the present invention comprises assembling the grid, framework, and facing members with a suitable glue or other adhesive interposed between the parts; ap-

plying external heat and pressure to the parts to bond the same together; and simultaneously therewith applying pressure internally of the said assembly to prevent collapsing or injury to the soft grid, and for retaining the said facing members flat during the glue setting operation.

For a better understanding of the invention, reference is made to the accompanying drawing in which:

10 Figure 1 is a perspective view of a door made in accordance with the teachings of this invention, with parts broken away for clearness of illustration;

15 Figure 2 is a perspective view on an enlarged scale of the grid or filler of the door with one of the ribs broken away to show the ventilating slots 16c;

20 Figure 3 is an enlarged view of a portion of one of the ribs of the grid to illustrate more clearly the ventilating slots 16c;

Figure 4 is a side elevation of a multiple hot-plate press having a plurality of the aforesaid structural units lodged therein for processing;

25 Figure 5 is an enlarged view, partly in section, of the combination valve and connecting plug employed to place pressure within the structural assembly, and illustrating the pressure valve closed;

30 Figure 6 is an enlarged view, partly in section, of the combination valve and connecting plug, illustrating the pressure valve open, and the connecting plug sealed in the aperture 15 of the aforesaid structural assembly.

While I have shown a fabricated or built-up 35 grid for the door, it is to be understood that a machined or molded grid, similar to that shown in Figures 3 and 4 of the aforesaid patent to G. D. Kellogg, may be substituted without departing from the spirit of the invention. Similarly, while I have omitted the incombustible sheets of asbestos placed between the grid and facing members, it is to be understood that these may be used without departing from the spirit of my invention.

40 45 With reference to Figure 1, it will be observed that the structural unit is illustrated in the form of a door having a grid, or lattice-work filler 16 of relatively soft material, a framework comprising rails 24 and stiles 26 of relatively hard material, and facing members 12, which members preferably consist of composite piles of wood veneer, the grain of one ply 22 being arranged cross-wise with respect to the grain of the ply 21.

50 55 The grid 16 preferably consists of two series of intercrossed strips 16a of fibrous or other rela-

tively soft material, in which the strips in a given series extend substantially parallel to each other and at an angle to the strips in the other of the said series. The strips of each series are preferably notched at 16b, as illustrated in Figures 2 and 3, so that the strips interlock at the cross-over points between the strips of the two series. Figure 1 clearly illustrates this arrangement, and the enlarged detail of the grid 16 shown in Figure 2 clearly shows the interlocked relation of the strips at the crossover points. It is also to be understood that the notches 16b may be alternately arranged along the opposite edges of the strips 16a, so that the grid will become an inseparable, interlocked-assembly, when the facing members are secured thereto.

With further reference to Figures 1 and 2, it will be apparent that the interlocked strips 16a of the grid 16 form a plurality of compartments, which, when the facing members are secured thereto form a plurality of closed compartments. Therefore, to provide a communication between the various compartments, an auxiliary notch 16c is cut adjacent each notch 16b. Figures 2 and 3 particularly illustrate this construction, and it is to be understood that various other means may be employed to provide the required communication between the various chambers, such as holes in the faces of the strips 16a.

In order to minimize twisting of the several strips along the longitudinal axis thereof, the strips 16a are made thick (broad) on their edges, and of relatively soft and lightweight material such as the fibre insulating board previously mentioned. Strips having a thickness of one-half inch, or more, have been found to be satisfactory, and it has been observed that strips of this thickness provide sufficient contact area with the inside surfaces of the facing members to obtain a satisfactory glue joint with the adhesive 17.

The adhesive 17 may be one of the organic or inorganic adhesives such as sodium silicate, calcium silicate, calcium aluminate, phenol-aldehyde resin or casein, and it is to be understood that the adhesive is distributed substantially continuously over the areas of contact between the grid and facing members, and over the areas of contact between the framework and facing members. It is to be understood also that the abutting edges of the rails 24 and stiles 26 may be mortised or dove-tailed to provide additional mechanical strength for the framework without departing from the spirit of this invention. Likewise, it is to be understood that the framework is preferably constructed of wood or other relatively hard material having the required proportions to accommodate conventional hardware such as latches, door knobs, hinges, etc.

As illustrated in Figure 1, the facing members 12 preferably consist of composite plies of wood veneer having the grain of one ply 22 arranged crosswise with respect to the grain of the ply 21. A conventional water-resistant adhesive 23 secures the plies together, and, as well known in the art, such an adhesive may comprise a composition including, casein or phenol-aldehyde resin.

As indicated in Figures 1, 4, 5 and 6, the rail 24 is provided with an aperture 15 for receiving a connection to a fluid pressure such as steam or air.

With reference to Figure 5, it will be observed that the connection comprises a conduit 14, which conduit is connected to a suitable source of fluid pressure. A valve 11 is interposed in the conduit 14, which valve is opened and closed by the handle 13. In Figure 5 the valve is illustrated in a

closed condition, while, in Figure 6, the valve is illustrated in open condition.

As further illustrated in Figure 5, the conduit 14 is enlarged at 6, and a sleeve 8 is slidably mounted thereon. A rubber sleeve 7 is disposed upon conduit 14 between the enlarged end 6 and slideable sleeve 8. It is to be observed that handle 13 is provided with cams 10, one on each side of valve 11, that engage the slideable sleeve 8, and that the cams 10 are constructed and arranged to move the sleeve 8, longitudinally along the conduit 14 and compress the rubber sleeve 7, when the valve 11 is moved to an open condition.

Thus, as illustrated in Figure 6, when the connector is inserted into the aperture 15 in the door rail, and the valve handle 13 actuated to open the valve, the rubber sleeve 7 is compressed, thereby sealing the connection in the said aperture. Similarly, when the valve handle 13 is actuated to close the valve, the rubber sleeve 7 restores to its normal shape, as illustrated in Figure 5, thereby enabling the connector to be easily withdrawn from the aperture 15.

A conventional hot-plate press is illustrated in Figure 4, which press is shown loaded with a plurality of doors for processing. The numerals 24 and 26 designate the rails and stiles of the respective doors, and the numeral 15 designates the aperture into which the pressure connector is inserted.

As illustrated in Figure 4, each door assembly is disposed between conventional heated-platens, which platens are connected, via suitable flexible-connections, to a steam supply-line 25 for heating the respective plates. The top platen 27a is usually fixed to the upper cross-head 22 of the press, while the intervening platens 27 are slidably mounted between the tie-rods 21. The usual discharge pipes for the platens are not shown, and it is to be understood that these are provided.

It is also to be understood that the press is provided with a suitable means for retaining the platens in open or spaced relation, when the ram 18 is lowered, which means is represented by rods 19 upon which the platens rest when the ram 18 is lowered. The numeral 20 designates a conduit connection to a fluid pressure unit for actuating the ram 18.

In practicing the present invention the grids 16, rails 24, stiles 26 and facing members 12 are assembled with the proper adhesive distributed uniformly and continuously between the abutting edges and surfaces of the various parts. The doors thus assembled are then loaded into a heated platen press, as illustrated in Figure 4.

A pressure connector is inserted into each rail aperture 15, and, substantially simultaneously with the application of external pressure to the door assemblies via ram 18, fluid pressure, preferably air, is applied via each respective pressure connection into the interior of each door assembly. While not shown, it is to be understood that a master valve may be associated with the fluid pressure connection from conduits 14, which master valve serves to apply and remove pressure from all conduit connections 14 simultaneously.

In commercial processing of doors having two-ply facing-members, and cores of relatively-soft fibrous-material, an external pressure of approximately 100 lbs. per square inch is applied by the ram of the platen press, while an internal pressure of approximately 80 lbs. per square inch is directed into the interior of each door assembly via the conduits 14 and apertures 15.

With pressures as aforesaid, complete bond-

ing of the glue joints are effected in approximately 6 minutes, when the platens are maintained at a temperature of 250 to 280° F.

Therefore, it will be evident that, during processing, the platen press provides heat and pressure for curing the adhesive thus bonding the parts into an integral structure, and the internally applied pressure forces the facing members 12 into perfectly flat engagement with the faces of the platens and retains them in this condition throughout the bonding operation. Thus, the facing members 12 are retained perfectly flat and the relatively-soft grid 16 is protected against the otherwise injurious effects of the 100 lb. pressure applied by the platen press alone.

Having thus described my invention, I claim:

1. The method of making a hollow structural unit having two facing members of relatively thin material and a core structure between the facing members composed of a frame of relatively hard material and spacer members of relatively soft material disposed within the frame which comprises; assembling the facing members and the core structure as aforesaid with an adhesive interposed between the abutting faces thereof; applying a relatively high pressure to the external face of each facing member, and substantially simultaneously therewith applying a lower pressure to the internal face of each facing member to oppose the relatively higher pressure applied to the external faces of the facing members.

2. The method of making a hollow structural unit having two facing members of relatively thin material and a core structure between the facing members composed of a frame of relatively hard material and an element of relatively soft material disposed within the frame for spacing the said facing members which comprises; assembling the facing members and the core structure as aforesaid with an adhesive between the abutting faces thereof; applying pressure to the external face of each facing member, and substantially simultaneously therewith applying pressure fluid into the interior of the hollow unit having a pressure lower than that applied to the facing members, to oppose the higher pressure applied to the external faces of the facing members; and heating the structural unit while maintaining the pressures as aforesaid to bond the aforesaid abutting faces by the adhesive interposed therebetween.

3. The method of making a hollow structural unit having two facing members of relatively thin material and a core structure between the facing members composed of a frame of relatively hard material and an element of relatively soft material disposed within the frame for spacing the said facing members which comprises; assembling the facing members and the core structure as aforesaid with an adhesive interposed between the abutting faces thereof; applying pressure at approximately 100 lbs. per square inch to the external faces of the facing members and substantially simultaneously therewith applying pressure fluid into the interior of the hollow unit at approximately 80 lbs. per square inch to oppose the pressure applied to the external faces of the facing members.

4. The method of making a hollow panel having two facing lamina of relatively thin material and a core structure between the facing lamina composed of a perimetrical frame of relatively hard material and spacer members within the frame of relatively soft material, which comprises; assembling the facing lamina and the core structure as aforesaid with an adhesive interposed between the abutting faces of the core and facing lamina; applying heat and pressure to the external face of each facing lamina sufficient to effect bonding of the aforesaid abutting faces, and, simultaneously therewith, applying pressure fluid into the interior of the hollow panel at a pressure less than that applied to the external faces of the lamina but sufficient to prevent collapse of the spacer members of the core structure.

5. The method of making a hollow structural unit having two facing members of relatively thin material and a core structure between the facing members composed of intercrossed strips of relatively soft material and a frame of relatively hard material surrounding the edges thereof, which comprises; assembling the facing members and the core structure as aforesaid with an adhesive interposed between the abutting faces thereof; applying heat at approximately 250° to 280° F. and pressure at approximately 100 lbs. per square inch to the external faces of the facing members, and, simultaneously therewith, applying pressure fluid into the hollow spaces between the facing members formed by the intercrossed strips and frame at approximately 80 lbs. per square inch.

6. The method of making a hollow panel having two facing lamina of relatively thin material and a core structure between the facing lamina composed of a perimetrical frame of relatively hard material and spacer members within the frame of relatively soft material, which comprises; assembling the facing lamina and the core structure as aforesaid with an adhesive interposed between the abutting faces of the core and facing lamina; applying heat and pressure to the external face of each facing lamina, and, simultaneously therewith, applying pressure fluid into the interior of the hollow panel at a pressure less than that applied to the external faces of the facing lamina.

7. The method of making a hollow panel having two facing members of relatively thin material and a core structure between the facing members composed of a perimetrical frame of relatively hard material and an element of relatively soft material within the frame for spacing the said facing members, which comprises; assembling the facing members and the core structure as aforesaid with an adhesive interposed between the abutting faces thereof; clamping the internal faces of the facing members to the abutting faces of the core structure under pressure to effect bonding therebetween, and, substantially simultaneously therewith, applying pressure fluid into the interior of the hollow panel at a pressure less than the aforesaid bonding pressure but sufficient to prevent collapse of the spacer elements of the core structure.

OLIVER CLARENCE DAVIS.
